UNITED STATES PATENT OFFICE.

WALDEMAR J. WEGLENER, OF HIGHWOOD, ENGLEWOOD, NEW JERSEY, ASSIGNOR TO
THE KNY-SCHEERER CORPORATION, A CORPORATION OF NEW YORK.

CONTAINER FOR STERILIZERS.

1,357,754.

Specification of Letters Patent. Patented Nov. 2, 1920.

Application filed September 14, 1918. Serial No. 254,094.

To all whom it may concern:

Be it known that I, WALDEMAR J. WEGLENER, a citizen of the United States, and a resident of Highwood, Englewood, county of 5 Bergen, and State of New Jersey, have invented certain new and useful Improvements in Containers for Sterilizers, set forth in the following specification.

This invention relates to apparatus for 10 accomplishing the sterilization of bandages, sponges, clothing and other articles.

Heretofore sterilizers cylindrical in form, mounted so that their axes are horizontal, have been employed for the purpose of sterilizing cloths and other articles incident to 15 operations. It has been customary to pack the articles to be sterilized in metallic, cylindrical containers, several containers to a sterilizer. About the periphery of the container, localized principally in an equatorial band, are openable and closable perforations.

The object of the present invention is to increase the thoroughness of sterilization. In carrying out this object it is a further object of this invention to provide a sterilizable 25 package in which sterilization may be accomplished not only from the outside toward the inside but from the outside toward the inside and from the inside toward the outside.

In carrying out the functions of this invention the usual mechanism employed is a sterilizer which comprises a cylindrical shell, the axis of which is horizontal and into the 35 top of which live steam is introduced under pressure. This invention has to do particularly with a modification of the container. It is an object to design such a container that when filled, the steam introduced shall 40 have more ready effectiveness in displacing the air imprisoned in the articles to be sterilized and, furthermore, so that the steam shall be able to penetrate throughout the entire package more quickly.

45 With such a sterilizer, which has cylindrical form and in which steam is to be admitted at the upper portion or in fact any portion, because live steam rises to the upper portion, it is preferable that the packages 50 to be sterilized be limited to such forms, shapes or configurations that are most easily handled. It has been found that such a package as an individual entity is preferably a cylindrical package.

55 Heretofore cylindrical containers have

been employed as individual containers for articles necessary to be sterilized. Such containers have, for the purpose of insulating sterilization, been provided with controllable, equatorially arranged openings. 60 Such openings, however, have been operable solely to insure the initial entrance of live steam for the purposes of sterilization, but the complete entrance of live steam to effect sterilization throughout the entire cross 65 section of a package to be sterilized has been not only slow but, in most cases, haphazard if not always incomplete.

More particularly, an object of the present invention is to modify the usual form of 70 container confining an individual package of articles to be sterilized so that a distribution of the sterilizing agent may take place not only from the exterior but also from the interior of the package. To this end means 75 for forming a sterilizable package is contemplated of such a character that exterior portions of a cylindrical arrangement are exposed to a sterilizing agent and, in addition thereto, so that interior portions, preferably axially arranged, are also exposed to the said sterilizing action. It may be that the arrangement of the exterior and interior portions are such that the sterilizing agents may have action, first upon the exterior to 85 expel the air contained in the articles to be sterilized and, at the same or approximately 80 the same time, to apply the sterilizing agent to the interior of the said articles arranged in cylindrical form so that complete sterilization is effected. 90

Furthermore, this invention relates to the specific details of constructions of a sterilizable package which is described below in its preferred embodiment and which, in 95 similar manner, is illustrated in the drawings, showing the same merely for the purpose of illustration, which accompany this application as a part hereof, and in the several figures of which like characters 100 designate corresponding parts.

In the drawings—

Figure 1 is a cross section of a sterilizable unit in combination with a sterilizer for co-operation therewith;

Fig. 2 is a front elevation of the sterilizable unit shown in Fig. 1;

Fig. 3 is a section through line III—III of Fig. 4 of a modification of a sterilizable unit as shown in Fig. 4;

110

Fig. 4 is a section through the modified sterilizable unit shown in cross section in Fig. 3;

Fig. 5 is a section corresponding to Fig. 4 of a basket formation serviceable to form a sterilizable unit within the scope of the invention; and

Fig. 6 is a section through line VI—VI of Fig. 5 of the structure shown in Fig. 5 but including, in addition, the necessary container of portable cylindrical form for use with the basket of Figs. 5 and 6.

In connection with the present invention it is to be understood that a sterilizer of usual form is contemplated,—that is, such a sterilizer which commonly has cylindrical form with its axis arranged horizontally and with a supply of live steam into its top portion and with control ports at or near the bottom so that the initial charge of air may be permitted to exit, as well as water from condensed steam. Such a sterilizer is indicated generically in the accompanying drawings by the character A.

As has been previously pointed out, the present invention has to do particularly with the units containing articles to be sterilized which, as units, are introduced into the sterilizer A. These units, in so far as their design is concerned, are controlled not only by the necessity of insertion within the sterilizer A upon runways 1, but in addition by the necessity of ready manual manipulation both before they are inserted within the sterilizer and after they have been removed therefrom. The most convenient form to satisfy these various conditions is that of a cylinder.

For all modifications of this invention, therefore, it is to be understood that the primary containing unit in cylindrical form be the unit B. In this unit a cylindrical shell 2 is provided with lateral perforations 3 in two or more series about its cylindrical contour. An adjustable slip sleeve 4 encircles the cylindrical part of this shell and is mechanically guided by spun beads 5. This sleeve 4 is perforated with perforations 6, coincident with the perforations 3, when coincidence is desired, but the sleeve 4 is provided with a clamping bail 8, the construction of which, in Fig. 2, is shown unclamped so that the entire sleeve 4 may be rotated about the cylindrical formation 2 so that coincidence between the perforations 3 and 6 no longer takes place to close the interior. In either of the positions of adjustment, coincidence or lack of coincidence between the perforations 3 and 6, the sleeve 4 may be clamped by a swinging over of the clamping bail 8 so that the sleeve 4 is fixed in its clamped position. The unit container so far described, with its slip sleeve 4, has a bottom closure 9 and a cover 10 hinged to the body portion by the hinge 11.

and securable by the hasps 12. This container for a sterilizable charge 13, which indicates indiscriminately a multiplicity of bandages, surgical gowns, sponges and so forth, is not claimed itself as the invention. Heretofore it has been customary to charge shell units of this character with a full content of textile articles to be sterilized. According to this method, the live steam introduced at the top of the sterilizer A has been required to penetrate the articles 13 to be sterilized progressively from the top downward to the ultimate bottom position after displacing the air contained or pocketed within the articles to be sterilized. Thus, according to the old process, insulation against sterilization has been dependent upon the full diameter of the cylindrical package to be sterilized, sterilization being dependent upon the penetration of live steam through the entire package from the top to the bottom, or at best from the cylindrical exterior to the center. According to the present invention, no modification of the exterior container for sterilizable packages is contemplated, that is, for the exterior container B. It is, however, contemplated that means be provided to insure a more ready penetration of the sterilizing steam to the various parts of the package to be sterilized.

To this end, in the preferred embodiment of the invention, a cylindrical pan C is provided, having a bead 14 fitting snugly against the interior of the cylindrical portion 2 of the shell B, so that its cylindrical wall 15 is spaced a material distance apart therefrom to provide a cylindrical passage space 16. The bottom 17 of this pan C is spaced apart from the bottom wall of the container B by suitable spacing means such as the detents or feet 18, thus providing a circulation space 19. Formed integrally with the bottom 17 is an axial tube 20 having lateral perforations 21, it being understood that the said tube 20 may not of necessity be a separate structure suitably secured to the bottom 17. When the pan C together with its axial tube 20 is nested within the container B the exterior and central circulation passages are formed as contemplated within the invention. At this point it is to be understood that the slipping function of the sleeve 4, so that the perforations 3 and 6 may be brought into and out of coincidence, is important as to whether or not the container B is or is not to be placed within the sterilizer A. If it is within the sterilizer A the perforations should be coincident to permit the ready passage of the sterilizing medium such as steam. When the container B is removed from the sterilizer A the slip ring 4 should be shifted so that no coincidence between the perforations takes place,—in other words, so that the container B is a complete inclosure

to prevent the accidental ingress of contaminating influences.

In operation, the structure illustrated in Figs. 1 and 2 is such that the sterilizing steam is forced through the coincident apertures 6 and 3 from the space 25 initially supplied with steam within the sterilizer A. Part of this sterilizing steam passes downward through the articles 13 to be sterilized. 10 Another part passes in the direction of the arrows through the space 16 into the space 19 and thence into the interior of the tube 20 through the perforations 21 for a continued passage down through the articles 13 15 below the tube 20 where a final exit is accomplished through the lower perforations 26, 6 and 3, below which a suitable exit for the initial charge of air has been provided by the sterilizer A. After the charge within 20 the container B has been completely sterilized, containers B may be removed from the sterilizer A for the desired surgical use.

As a modification of the apparatus, instead of the pan C and its tubular connection 20, which is to be fabricated as a separate entity from the container B, it is contemplated that the desired passages for the distribution of the sterilizing medium may be formed as integral parts of the container 25 B as shown particularly in Figs. 3 and 4. In these figures a plurality of ducts 28, extending radially across the bottom 29 of the container B with elemental extensions 30 embracing perforations 3 through the container B are provided. These ducts are formed preferably from channel-strips soldered to the container B and centrally terminate to discharge into an axial tube or conduit 31 having perforations 32, the duct 40 31 corresponding to the similar duct or tube 20 having similar perforations 21. In other respects, the container B is identical with that described and illustrated in connection with Figs. 1 and 2.

45 It may be desired to carry out the functions of this invention in a second modified manner,—for example, that made possible by the apparatus illustrated in Figs. 5 and 6. In this embodiment it is to be understood that the container B of Figs. 1 and 2 is to be employed exactly as has been described but that a nesting basket D be employed, formed suitably from wire uprights 34 and wire basket work 35, all of a shape 50 and configuration to nest within the container B and having feet 36 or a wire rim 36 capable of elevating the basket D above the bottom of the container B. It is also contemplated that a set of uprights 37 be 55 formed axially of the basket D, which should be surrounded with basket work 38 so that functionally a perforated tube 39 is formed. When the basket structure D is inserted within the container B after it has 60 been packed with articles for sterilization 65

suitable passages are necessarily formed from the openings 6 and 3 down along the bottom 40 of the container B into the tubular space between the articles formed by the tubular basket work 39 so that the functioning effect of the pan and tubular structure of Figs. 1 and 2 is reproduced. 79

Although I have illustrated and described suitable embodiments of my invention, I am not limiting myself to any one of the embodiments illustrated and described, but contemplate that the full scope of my invention shall be demarcated by the scope of my accompanying claims. 75

What I claim and what I desire to secure 80 by United States Letters Patent is:—

1. A container for sterilizing a package comprising a cylindrical shell having circumferentially disposed perforations; and means for confining the charge to be sterilized so that passages be maintained both between said shell and the exterior of said charge and axially into the interior of said charge, for the distribution of a sterilizing medium. 90

2. A container for sterilizing a package comprising a cylindrical shell having circumferentially disposed perforations; a slip-sleeve overlying said cylindrical shell and having perforations registerable with 95 said circumferentially disposed perforations for the purpose of opening, and closing the same by the circumferential slipping of said sleeve; and means for confining the charge to be sterilized so that passages be maintained both between said shell and the exterior of said charge and axially into the interior of said charge, for the distribution of a sterilizing medium applied exteriorly to said shell. 100

3. A sterilizing container comprising a cylindrical shell having perforations for the passage of a sterilizing medium; and interior means for confining a charge to be sterilized so that passages be maintained 110 and provided between the exterior of said charge and said shell and from the exterior of said charge for a considerable axial extent within the interior of said charge.

4. A sterilizing container comprising a 115 metallic container in cylindrical form having lateral openings; means for confining an interior charge of articles to be sterilized so that a peripheral space between said container and said charge is maintained; and 120 means providing an axial opening into the interior of said charge is gaseous communication with said peripheral space.

5. A container for purposes of sterilization comprising a cylindrical metallic shell 125 having closures for both ends in combination with an auxiliary pan in the form of a cylindrical dish having spacing means to separate the same from said container; and an axial, tubular, perforated formation on 130

said pan, whereby the distribution of sterilizing gas may take place both exteriorly and interiorly of the said charge to be sterilized.

5 6. A sterilizing container comprising a sheet metal shell having closable perforations and an openable closing cover, in combination with interior confining means for direct contact with a charge of articles to be

sterilized for maintaining an open passage-way for the sterilizing medium from the perforations of said shell about said charge and freely into the interior of said charge. 10

In testimony whereof I have signed my name to this specification, this 13th day of 15 August, 1918.

WALDEMAR J. WEGLENER.
